SAFETY RAZOR

Jacob Oberheim, New York, N. Y.

Application April 19, 1946, Serial No. 663,546

3 Claims. (Cl. 30—58)

1

This invention relates to safety razors and in particular is directed to certain novel improvements in the design and construction thereof.

It is among the objects of my invention to provide a safety razor comprising a minimum number of parts.

Another object is to provide a safety razor which may be inexpensively produced.

A further object is to provide a safety razor which may be rapidly assembled and disassembled, and which does not require disassembly for removal or replacement of the blade, or for cleaning operations.

An additional object is to provide a structure of the class indicated, resulting in economy of materials, and which is particularly adapted for use with an extremely narrow blade.

The foregoing and other objects will become apparent upon consideration of the accompanying drawings and the description thereof wherein:

Fig. 1 is an exploded view illustrating one embodiment of my invention showing the various parts thereof.

Fig. 2 is a perspective view of the structure shown in Fig. 1 in assembled relationship.

Fig. 3 is a detailed view partly broken away, showing an alternative construction of the lower portion of the safety razor illustrated in Fig. 2.

Fig. 4 is a vertical section of the upper portion of the safety razor shown in Fig. 2 illustrating its closed or clamped position.

Fig. 5 is a view of the upper portion of the safety razor shown in Fig. 4 but illustrating the same in open position for removal or replacement of the razor blade.

The hollow generally cylindrical handle 10 is externally threaded at its upper end as indicated at 11 to receive the collar 12 internally threaded as at 13 of the guard member 14. The guard member 14 may be provided with teeth 15 extending along its anterior lateral edge and the terminal lugs or projections 16 which serve to align the inserted razor blade 17. The pins 18 serve additionally to locate and align the blade 17 which may be provided with holes 20, spatially arranged to fit over the pins 18. The guard member 14 is formed in such a manner as to present a rearwardly projecting portion 21 having its lower end provided with the collar 12 internally threaded as hereinbefore described. The member 21 is also provided with vertical upwardly extending flanges 22. The clamping member 23 may be pivotally attached to the flanges 22 of the guard member 14, by means of a threaded pin 24 which passes through oppo-

2

sitely-disposed holes 25 in the outer flanges 26 of the clamping member 23 and the corresponding holes 27 of the flanges 22 of the guard member 14. The clamping member 23 may have a length equal to that of the guard member 14, and be provided with downwardly projecting lugs 28, which abut the ends 29 of the guard member 14, and which are in alignment with the terminal lugs 16 in the closed position of the safety razor.

The clamping member 23 may be provided with a downwardly extending portion 30 centrally disposed between the outer flanges 22 and defining an angularly-inclined raceway or channel 31 having a constricted lower portion for the purposes to be hereinafter indicated.

The cylindrical handle is internally threaded as at 32 to receive a screw spindle 33 threaded as at 34. The screw spindle 33 terminates upwardly in a structure adopted for complementary insertion within the raceway or channel 31. The terminal portion of the screw spindle 33 may conveniently take the form of a ball-tip 35, as shown in the drawings.

Upon assembly, the ball-tip 35 of the screw spindle 33 is retained within the angularly-inclined channel 31 of the clamping member 23. Pivotal movement of the clamping member 23 with respect to the guard member 14 may be achieved by advancement of the screw spindle 33. This movement may conveniently be accomplished by rotating the knurled lower end 37 of the screw spindle 33. Removal of the blade may be effected by rotating the knurled end 37 of the screw spindle 33 in a reverse direction to move the clamping member 23 away from the guard member 14, thereby freeing the blade 17, as illustrated in Fig. 5.

The alternative embodiment of the principle of my invention showing a modification of structure and co-action between the handle 40, the non-threaded spindle 41, and the clamping member 23, is illustrated in Fig. 3. This arrangement contemplates the use of a bayonet slot 42 disposed conveniently at the lower end of the handle 40 adapted to engage and retain a bayonet pin 43 projecting from the spindle 41. In the illustration thereof, as shown in Fig. 3, the razor is in the closed position analogous to that illustrated in Fig. 4 for the previously described embodiment. The razor may be opened so as to separate the clamping and guard members by turning the knurled end 44 of the spindle 41 (which is not threaded as contrasted with the threading 34 of the screw spindle 33) thereby bringing the pin 43 into alignment with the

longitudinal portion of the bayonet slot and thereupon pulling the spindle 41 away from the handle 40.

Since other modifications in the safety razor which embody the invention may be made without departing from its scope, it is intended that all matter contained in the above description or shown in the accompanying drawings shall be interpreted as illustrative and not in a limiting sense.

Having described my invention and illustrated its use, what I claim is new and desire to secure by Letters Patent is:

1. A safety razor comprising a handle having a hollow bore, a guard member having a longitudinally disposed bed for a razor blade and a centrally positioned and rearwardly projecting section adapted to engage said handle, said section having a pair of upwardly disposed and spaced-apart flanges, a blade clamping member having a centrally positioned and rearwardly projecting section, said section of the clamping member having a pair of downwardly disposed and spaced-apart flanges, said section of the clamping member also having a centrally disposed portion with an arcuately and downwardly extending slot, said slot opening into a second larger slot of substantially circular cross section, a pin extending through all the aforesaid flanges whereby the guard member and clamping member are held in pivotal connection, a spindle extending within said handle, the upper end of said spindle having a tapered portion carrying a ball, the said ball being held slideably in the aforesaid circular slot and the tapered portion within the first mentioned slot, whereby motion of said spindle serves to move the clamping member, thereby to lock a blade positioned between said clamping member and the guard member.

2. A safety razor comprising a tubular internally threaded handle, a guard member having a longitudinally disposed bed for a razor blade, and a centrally positioned and rearwardly projecting section adapted to engage said handle, said section having a pair of upwardly disposed and spaced-apart flanges, a blade clamping member having a centrally positioned and rearwardly projecting section, said section of the clamping member having a pair of downwardly disposed and spaced-apart flanges, said section of the clamping member also having a centrally disposed portion with an arcuately and downwardly extending slot, said slot opening into a second larger slot of substantially circular cross section, means for pivotally connecting the pair of flanges

of the rearwardly projecting section of the guard member with the pair of flanges of the rearwardly projecting motion of the clamping member, a spindle threadedly engaged within the internal threads of the handle and extending therethrough, the upper end of said spindle having a tapered portion carrying a ball, the said ball being held slideably in the aforesaid circular slot and the tapered portion within the first-mentioned slot, whereby motion of said spindle serves to move the clamping member thereby to lock a blade positioned between said clamping member and guard member.

3. A safety razor comprising an internally threaded tubular handle, a guard member having a longitudinally disposed bed for a razor blade, and a centrally positioned and rearwardly projecting section adapted to engage said handle, said section having a pair of upwardly disposed and spaced-apart flanges, a blade clamping member having a centrally positioned and rearwardly projecting section, said section of the clamping member having a pair of downwardly disposed and spaced-apart flanges, said section of the clamping member also having a centrally disposed portion with an arcuately and downwardly extending slot, said slot communicating with a channel parallel with said slot and of larger transverse cross section than the cross section of said slot, means for pivotally connecting the pair of flanges of the rearwardly projecting section of the guard member with the pairs of flanges of the rearwardly projecting section of the clamping member, a spindle threadedly engaged within and extending through said handle, said spindle terminating in a section, of reduced diameter, extending through the aforesaid slot and carrying a terminal tip of larger diameter than the said section, said tip being held in slideable engagement within the aforesaid channel, whereby motion of said spindle serves to move the clamping member thereby to lock a blade positioned between said clamping member and guard member.
